UNITED STATES PATENT OFFICE.

ALBERTUS B. MATTINGLY, OF NEW YORK, N. Y.

ATTACHMENT FOR SEWING MACHINES.

Substitute for application Serial No. 10,505, filed February 25, 1915; Renewed December 28, 1922. This application filed September 10, 1923; Serial No. 662,003.

To all whom it may concern:

Be it known that I, ALBERTUS B. MATTINGLY, citizen of the United States, and resident of New York, in the county of New

5 York and State of New York, have invented certain new and useful Improvements in Attachments for Sewing Machines, of which the following is a specification.

This invention relates to an improvement 10 in attachments for sewing machines, and the inventor is aware that the device is of a nature similar to that disclosed in British Letters Patent No. 17,153 of 1905, to Hills, and United States Patents No. 412,081, to 15 Fletcher, No. 990,601, to Seward, and No. 990,610, to Turck, and the object is to overcome some of the objectionable features of these devices and to further improve the same.

20 This application is substituted for my prior application, Serial Number 10,505, filed on February 25, 1915, and which was renewed on December 28, 1922.

The principal objects are to provide a 25 device of this character to automatically cut or slit the cloth just in advance of the stitching or binding of the button-hole so that the needle may pass alternately through the cloth and then through the slit or cut, thus 30 causing the thread to be brought through the cut and make a perfect binding of the raw edges of the work, and to provide a 35 means for positively actuating the knife, so as to give it a quick and decisive action at the proper periods to make the cut the 40 proper length according to the length of the button-holes, and to have the length of cut automatically adjust itself with the adjusting of the device for the length of the button-hole.

The further objects are to provide a 45 device of this character which by its construction is considerably reduced in height and thereby doing away with the necessity of removing the face plate of the sewing machine to adjust the presser bar, and by the construction of the base plate obviating the necessity of removing the feed dogs of the 50 sewing machine, (both of which things have to be done before the Hills or Turck devices can be attached to the machine).

The still further objects are to provide an 55 improved ratchet device for effecting the lateral vibration of the work clamp, to produce the overstitch of the edge of the but-

ton-hole, and to form other parts of the device by the stamping process, and by screw machines, which are the cheapest methods of manufacturing of this class.

A still further object is to provide a 60 device of this kind in which the knife can be adjusted to cut a line or slit in which the needle will follow with its inside lines of its vibrating motion on its forward movement and also perform the same function 65 on its backward movement in forming or stitching the button-hole.

With these and other objects in view, it will be seen that I accomplish the foregoing, 70 by referring to the accompanying drawings forming a part of this specification; but I do not wish to confine myself to the exact construction shown, as I have, for the sake of clear illustration, exaggerated some of the parts, especially in the side elevations. 75

In the accompanying drawings, showing one embodiment of my invention, Figure 1 is a plan view of the device; Fig. 2 is a side elevation; Fig. 3 is a horizontal section taken on the line 3—3 of Fig. 2, and showing diagrammatically the operating cam friction drive or eccentric in dotted lines; Fig. 4 is a similar view to Fig. 3, showing more clearly the operating means for the knife; Fig. 5 is a similar view to Fig. 4, 85 with the knife and its operating means removed; Fig. 6 is a similar view to Fig. 5, with the work clamp and knife guide and also the retaining washer removed, and showing the vibrating mechanism; Fig. 7 is 90 a similar view to Fig. 6, showing a part of the vibrating mechanism removed and showing the pawl plate and the adjusting means for the knife, and the adjusting means for controlling the length of throw 95 of the vibrator; Fig. 8 is a central vertical section of the device; Fig. 9 is a perspective view of the operating lever; Figs. 10, 11 and 12 are three views of the vibrator; Fig. 13 is a plan of the vibrator carrier; Figs. 14 100 and 15 are two views of the knife carrier; Figs. 16 and 17 are two views of the ratchet cam; Figs. 18 and 19 are two views of the shield for the knife carrier, and integral therewith the stripper plate for the needle, 105 and the guide for the work clamp; Figs. 20 and 21 are two views of the pawl plate for operating the ratchet cam; Fig. 22 is a plan of the work clamp; Fig. 23 is a top plan of the eccentric operating mechanism, showing 110

- the adjustable eccentric cam; Fig. 24 is a bottom plan of the eccentric operating mechanism, showing the knife cam and the race cam for operating the work clamp for forming the contour of the button-hole when operated in conjunction with the eccentric cam; Figs. 25 and 26 are two views of the retaining washer; Fig. 27 is a plan of the friction washer or plate; and Figs. 28 and 29 are two views of the retaining stud or pivot; Figs. 30 and 31 are two views of the adjustable guide for the alining of the work-clamp with the needle of the sewing machine.
- 15 I provide a suitable base plate 1, which is secured to a rear throat plate 2 of the sewing machine in any suitable manner, but preferably screwed thereto, as shown in Figure 1 of the drawings.
- 20 The base plate 1 is provided with an ear 3, which is upwardly turned and carries the operating lever 4, which rocks on a pivot 5 formed of a large screw, the lever 4 being provided with a bifurcated end 6, which engages the shank of the screw of the tightening collar of the needle bar of the sewing machine. The lever 4 is further provided with an arc-shaped slot 7, through which passes the arm of the friction clutch, which receives its movement from the screw 8 in the ear 9 and the rear end 10 of the slot 7. The screw 8 is frictionally held from turning by the pressure of the spring 11 against its head and the ear 9. The lever 4 is further provided with an arm or extension which has an upturned bifurcated end 12, which operates the pawl plate 13 by the web portion 14.
- 25 The base plate 1 is further provided with a stud or pivot 15, which I have shown screwed into the base plate with its flange or enlargement 16 resting against the plate. Rotatably mounted upon the stud 15 and supported by the flange 16 is the pawl plate 13, (which is swung in an arc by the end 12 of the lever 4 in a forward and backward movement). Rotatably mounted upon the stud 15 and resting upon the pawl plate 13 is a ratchet cam 17, and above this, resting 30 on a shoulder 18 of the stud 15, is the retaining washer 19, and then the eccentric disk 20 carrying the adjustable eccentric cam 22, which is held in position by a T-bolt 23 and lock nut 24. The top of the stud 15 is provided with a friction washer 25, which is prevented from turning by the flat 26 of the washer and the flat 27 of the stud. The friction is caused by the tightening of the screw 28 of the stud, which causes the washer to press the disk 20 against the retaining washer 19.
- 35 The base plate 1 is further provided with a cut-away portion 29 having an ear 30 bent horizontally, and slightly above the bottom level of the base plate. Passing
- 30 through the slot 31 in the ear 30 is a screw 32 screwed into an L-shaped member 33 which has a slot 34 and an upturned ear 35 for adjusting it while the screw 32 is loose. The slot 34 is for receiving the bottom end of the pin 36 of the L-shaped member 37, which is provided with a slot 38 for adjusting it upon the base plate 1 by the screw 39, and it is also provided with an upturned ear 40 for adjusting it while the screw 39 is loose. The pin 36 is tight in the member 37 and its upper end forms a pivot for the vibrator 41, which is connected thereto by the hole 42 in the ear 43, and when assembled the ear 43 is capable of passing under the pawl plate 13, while the yoke 44 straddles the ratchet cam and rests upon the pawl plate 13.
- 35 The vibrator 41 is provided with an upturned bifurcated ear 45, which has two notches 46 in which slides the rear yoke 47 (of the work clamp 48), which straddles the stud 15 and rests on the retaining washer 19, which working in conjunction with the slots or notches 46 keeps the forward part 49 of the work clamp in proper contact with the base plate 1 and prevents the bottom stripper plate 50 from leaving the slotted way 51 in the base as it is oscillated by the work clamp in connection with the ears 52.
- 40 Mounted upon the yoke 47 is the guide or shield 53 for the knife carrier 54, having its front end 55 in the form of a stripping plate which slides in a groove or space 56 formed by a plate 57, which is forced into the upper jaw 58 of the work clamp. The rear end of the shield 53 is enlarged, forming a guide 59, by means of the downwardly extending flanges 60 fitting the yoke 47, which moves back and forth relatively to the stud 15. The rectangular opening 61 is of a width equal to the diameter of the upper end of the retaining washer which passes through it and prevents the shield 53 from moving back and forth but allows its rear end to be drawn laterally of the stud 15 in both directions by the pin 62 working in the cam groove 63 formed by the cams 64 and 65, (thus causing the vibrator to vibrate or oscillate the work clamp in the shape of a button-hole while the eccentric is moving the work clamp back and forth the length of the button-hole).
- 45 The base plate 1 is further provided with a stud or pivot 66, which is secured to the base plate 1 by a screw 67, and the stud 66 carries a ratchet cam 68, which is held in position by a T-bolt 69 and lock nut 70. The top of the stud 66 is provided with a friction washer 71, which is prevented from turning by the flat 72 of the washer and the flat 73 of the stud. The friction is caused by the tightening of the screw 74 of the stud, which causes the washer to press the ratchet cam 68 against the retaining washer 19.
- 50 The base plate 1 is further provided with a stud or pivot 75, which is secured to the base plate 1 by a screw 76, and the stud 75 carries a ratchet cam 77, which is held in position by a T-bolt 78 and lock nut 79. The top of the stud 75 is provided with a friction washer 80, which is prevented from turning by the flat 81 of the washer and the flat 82 of the stud. The friction is caused by the tightening of the screw 83 of the stud, which causes the washer to press the ratchet cam 77 against the retaining washer 19.
- 55 The base plate 1 is further provided with a stud or pivot 84, which is secured to the base plate 1 by a screw 85, and the stud 84 carries a ratchet cam 86, which is held in position by a T-bolt 87 and lock nut 88. The top of the stud 84 is provided with a friction washer 89, which is prevented from turning by the flat 90 of the washer and the flat 91 of the stud. The friction is caused by the tightening of the screw 92 of the stud, which causes the washer to press the ratchet cam 86 against the retaining washer 19.
- 60 The base plate 1 is further provided with a stud or pivot 93, which is secured to the base plate 1 by a screw 94, and the stud 93 carries a ratchet cam 95, which is held in position by a T-bolt 96 and lock nut 97. The top of the stud 93 is provided with a friction washer 98, which is prevented from turning by the flat 99 of the washer and the flat 100 of the stud. The friction is caused by the tightening of the screw 101 of the stud, which causes the washer to press the ratchet cam 95 against the retaining washer 19.
- 65 The base plate 1 is further provided with a stud or pivot 102, which is secured to the base plate 1 by a screw 103, and the stud 102 carries a ratchet cam 104, which is held in position by a T-bolt 105 and lock nut 106. The top of the stud 102 is provided with a friction washer 107, which is prevented from turning by the flat 108 of the washer and the flat 109 of the stud. The friction is caused by the tightening of the screw 110 of the stud, which causes the washer to press the ratchet cam 104 against the retaining washer 19.
- 70 The base plate 1 is further provided with a stud or pivot 111, which is secured to the base plate 1 by a screw 112, and the stud 111 carries a ratchet cam 113, which is held in position by a T-bolt 114 and lock nut 115. The top of the stud 111 is provided with a friction washer 116, which is prevented from turning by the flat 117 of the washer and the flat 118 of the stud. The friction is caused by the tightening of the screw 119 of the stud, which causes the washer to press the ratchet cam 113 against the retaining washer 19.
- 75 The base plate 1 is further provided with a stud or pivot 120, which is secured to the base plate 1 by a screw 121, and the stud 120 carries a ratchet cam 122, which is held in position by a T-bolt 123 and lock nut 124. The top of the stud 120 is provided with a friction washer 125, which is prevented from turning by the flat 126 of the washer and the flat 127 of the stud. The friction is caused by the tightening of the screw 128 of the stud, which causes the washer to press the ratchet cam 122 against the retaining washer 19.
- 80 The base plate 1 is further provided with a stud or pivot 129, which is secured to the base plate 1 by a screw 130, and the stud 129 carries a ratchet cam 131, which is held in position by a T-bolt 132 and lock nut 133. The top of the stud 129 is provided with a friction washer 134, which is prevented from turning by the flat 135 of the washer and the flat 136 of the stud. The friction is caused by the tightening of the screw 137 of the stud, which causes the washer to press the ratchet cam 131 against the retaining washer 19.
- 85 The base plate 1 is further provided with a stud or pivot 138, which is secured to the base plate 1 by a screw 139, and the stud 138 carries a ratchet cam 140, which is held in position by a T-bolt 141 and lock nut 142. The top of the stud 138 is provided with a friction washer 143, which is prevented from turning by the flat 144 of the washer and the flat 145 of the stud. The friction is caused by the tightening of the screw 146 of the stud, which causes the washer to press the ratchet cam 140 against the retaining washer 19.
- 90 The base plate 1 is further provided with a stud or pivot 147, which is secured to the base plate 1 by a screw 148, and the stud 147 carries a ratchet cam 149, which is held in position by a T-bolt 150 and lock nut 151. The top of the stud 147 is provided with a friction washer 152, which is prevented from turning by the flat 153 of the washer and the flat 154 of the stud. The friction is caused by the tightening of the screw 155 of the stud, which causes the washer to press the ratchet cam 149 against the retaining washer 19.
- 95 The base plate 1 is further provided with a stud or pivot 156, which is secured to the base plate 1 by a screw 157, and the stud 156 carries a ratchet cam 158, which is held in position by a T-bolt 159 and lock nut 160. The top of the stud 156 is provided with a friction washer 161, which is prevented from turning by the flat 162 of the washer and the flat 163 of the stud. The friction is caused by the tightening of the screw 164 of the stud, which causes the washer to press the ratchet cam 158 against the retaining washer 19.
- 100 The base plate 1 is further provided with a stud or pivot 165, which is secured to the base plate 1 by a screw 166, and the stud 165 carries a ratchet cam 167, which is held in position by a T-bolt 168 and lock nut 169. The top of the stud 165 is provided with a friction washer 170, which is prevented from turning by the flat 171 of the washer and the flat 172 of the stud. The friction is caused by the tightening of the screw 173 of the stud, which causes the washer to press the ratchet cam 167 against the retaining washer 19.
- 105 The base plate 1 is further provided with a stud or pivot 174, which is secured to the base plate 1 by a screw 175, and the stud 174 carries a ratchet cam 176, which is held in position by a T-bolt 177 and lock nut 178. The top of the stud 174 is provided with a friction washer 179, which is prevented from turning by the flat 180 of the washer and the flat 181 of the stud. The friction is caused by the tightening of the screw 182 of the stud, which causes the washer to press the ratchet cam 176 against the retaining washer 19.
- 110 The base plate 1 is further provided with a stud or pivot 183, which is secured to the base plate 1 by a screw 184, and the stud 183 carries a ratchet cam 185, which is held in position by a T-bolt 186 and lock nut 187. The top of the stud 183 is provided with a friction washer 188, which is prevented from turning by the flat 189 of the washer and the flat 190 of the stud. The friction is caused by the tightening of the screw 191 of the stud, which causes the washer to press the ratchet cam 185 against the retaining washer 19.
- 115 The base plate 1 is further provided with a stud or pivot 192, which is secured to the base plate 1 by a screw 193, and the stud 192 carries a ratchet cam 194, which is held in position by a T-bolt 195 and lock nut 196. The top of the stud 192 is provided with a friction washer 197, which is prevented from turning by the flat 198 of the washer and the flat 199 of the stud. The friction is caused by the tightening of the screw 200 of the stud, which causes the washer to press the ratchet cam 194 against the retaining washer 19.
- 120 The base plate 1 is further provided with a stud or pivot 201, which is secured to the base plate 1 by a screw 202, and the stud 201 carries a ratchet cam 203, which is held in position by a T-bolt 204 and lock nut 205. The top of the stud 201 is provided with a friction washer 206, which is prevented from turning by the flat 207 of the washer and the flat 208 of the stud. The friction is caused by the tightening of the screw 209 of the stud, which causes the washer to press the ratchet cam 203 against the retaining washer 19.
- 125 The base plate 1 is further provided with a stud or pivot 210, which is secured to the base plate 1 by a screw 211, and the stud 210 carries a ratchet cam 212, which is held in position by a T-bolt 213 and lock nut 214. The top of the stud 210 is provided with a friction washer 215, which is prevented from turning by the flat 216 of the washer and the flat 217 of the stud. The friction is caused by the tightening of the screw 218 of the stud, which causes the washer to press the ratchet cam 212 against the retaining washer 19.
- 130 The base plate 1 is further provided with a stud or pivot 219, which is secured to the base plate 1 by a screw 220, and the stud 219 carries a ratchet cam 221, which is held in position by a T-bolt 222 and lock nut 223. The top of the stud 219 is provided with a friction washer 224, which is prevented from turning by the flat 225 of the washer and the flat 226 of the stud. The friction is caused by the tightening of the screw 227 of the stud, which causes the washer to press the ratchet cam 221 against the retaining washer 19.

portion 75 which insures the keeping of the cam 74 and the cam face 200 always in contact. At a predetermined point the flange 73 forming the cam face 200 is cut 5 away or ends as at 201, and the yoke is so formed at this point as to have a clearance space 202 to prevent the yoke frame from hitting the cam 74 when the flexible part 75 of the yoke causes the yoke and knife to 10 move quickly back between the strokes of the needle and thus prevent the needle bar from striking the knife several times while it is being moved back from under the needle bar. This quick movement is caused 15 by the cam 74, which holds the yoke forward for the proper time, having an abrupt drop 203, so that while it is revolving on the stud 15 the point 204 passes the point 205 on the cam face 200. The face 206 is 20 so formed as to not interfere with the cam face 200 and this allows the yoke to move back with its full stroke at this point, which is accomplished on the upward stroke of the 25 needle bar.

25 The work clamp is provided with an eccentric yoke or member 76 having an elongated opening 77 in which works the adjustable eccentric cam 22 against the faces 78 and 79. (The revolving of the cam 22 around the stud 15 causes the work clamp to be moved back and forth relative to the needle.) The member 76 is secured to the work clamp 48 by means of screws 80, and the forward end is bifurcated and bent so 30 as to form bearings for the locking member 81, which is formed of a bent wire having a central portion 82 which acts in the capacity of a hand lever to operate the two end portions 83, which act upon the spring 35 extensions 84 (of the upper jaw 58) and which are riveted to the rear yoke 47 of the work clamp.

40 Mounted on the base plate 1 (see Fig. 7) is a spring member 85, which is held in position by the screws 86 and has an upwardly extending portion 87, which extends through the opening 88 of the pawl plate 13 and into the holes 89 of the ratchet cam 17. This prevents the ratchet cam from being turned 45 backwards by friction of the pawl 90 slipping out of any one of the holes 89 upon its backward movement after it has revolved 50 the ratchet cam one tenth of a turn.

55 The eccentric disk is revolved by a friction device 91 consisting of a ring 92 carrying a friction dog 93 which turns on a pivot 95 and is held in its biting position by a spring 94. The operation of the friction device will be described later on.

60 The base plate is further bent or formed so as to have a raised portion 97 through the center thereof, upon which the bottom of the work clamp slides and on which is cut the channel or groove 51 for the stripper 65 plate 50, which has an opening 98 somewhat

in the shape of a T. Beneath the stripper plate 50 in the base plate is an opening 99 to allow the needle to perform its functions. The raised portion 97 forms a channel or groove 100 (see Fig. 8), which allows the 70 free action of the feed dogs of the sewing machine and raises the device enough to permit the cutting of the cloth without the knife hitting the dogs on its downward stroke. 75

The operation of the device is very simple. The rear throat plate of the sewing machine is removed and the device is slipped in its place by the insertion of the throat plate 2 which is screwed to the device, and the shank 80 of the screw which holds the needle in position passes into the bifurcated end of the lever 4.

To make a button-hole, the work clamp is set by operating the sewing machine until 85 the extreme back position of the work clamp is reached and the needle is in its extreme upper position. The lever 82 of the locking member 81 is then pressed forward; (that is, in the direction of the needle), and forces 90 the ends 83 backwards and thus relieves the pressure of the springs 84, which allows the jaws of the work clamp to open. The cloth is inserted between the jaws and the lever 82 pushed back to its original position, thus 95 causing the upper jaw to force the cloth down into the concave opening in the lower jaw, and at the same time the flanges 96 of the upper jaw prevent the slipping of the cloth on the lower jaw and thus causes the 100 cloth to be stretched like a drum head. With the work clamp in this position the knife is in the dotted position shown in Fig. 2, and upon running the machine the needle bar strikes the top of the knife and forces it through the cloth each time the 105 needle descends, until the work clamp is almost at its extreme forward position, when the cam 74 is at the point where the point or nose 204 passes the point 205 and the flexible portion 75 of the yoke causes the 110 yoke to move swiftly back and draw the knife out of line with the needle bar before it has time to descend and strike it again, (as shown in full lines in Fig. 2), thus preventing further cutting, and the knife remains in this position until the button-hole 115 is finished.

The pin 62 is the pivot center upon which 120 the work clamp is oscillated by the vibrator 41. With each upward movement of the needle bar the lever 4 is raised, which in turn swings the pawl plate 13 sufficiently to have the pawl 90 enter one of the holes 89 of the ratchet cam and revolve it one tenth of 125 a revolution, which causes one of the pointed cam faces 101 to act on one side of the yoke 44 and cause the vibrator to swing to one side on its pivot 36. The face 102 prevents any overthrow of the vibrator. The next 130

stroke of the needle causes one of the pointed faces 101 to act on the opposite side of the yoke 44 and swing it in the opposite direction. This movement of the vibrator causes the work clamp to be oscillated on its pivot 62, such motion being transmitted through the ear 45 of the vibrator. While the vibrator is oscillating the work clamp in one direction or the other with every stroke of the needle to make the needle pass first through the cloth and then through the cut, the eccentric cam is slowly shoving the work clamp forward the length of the button-hole, the speed of the forward movement being regulated by the screw 8, which strikes the arm 93 of the friction clutch and forces the ring 92 back a predetermined amount, (upon the downward stroke of the needle). The rear end 10 of the slot 7, upon reaching the arm 93, (on the upward movement of the needle), forces the ring to move forward and the nose 108 to bite into the eccentric disk 20 and cause the eccentric disk to revolve, which causes the point 109 of the cam 22 to act upon the face 79 of the member 76 and shove the work clamp forward, and when the cam point 109, on the last half of the revolution of the eccentric disk 20, works against the face 78, it causes the work clamp to be drawn backwards. The revolving of the eccentric disk 20 causes the pivot 62 to shift its position relatively to the ear 45 and the stud 15. On the first part of the revolution of the disk 20 the pivot pin 62 is in that position of the cam groove 63 designated by the numeral 103, which causes the first straight part of the button-hole to be made. The parts 104 and 105 cause the pin 62 to first move further away from the stud 15 and then closer to the stud than it was at the start. This causes the eyelet of the button-hole to be made, and the part 106, causes the pin to stand still until the last straight part of the button-hole is finished, and the movement of the pin caused by the part 107 causes the two straight sides of the button-hole to be stitched together.

In order to make a large button-hole, the eccentric cam 22 is located out at the periphery of the disk 20, and the nearer the center of the disk 20 the cam 22 is located the smaller will be the button-hole; but no matter what the length of the button-hole is the knife will always move from under the needle bar at the same period of the operation of making the button-hole and will be pushed under the needle bar at the starting point, so that the slot will always be the proper length. When a large button-hole is made its overstitch should be of greater length than for a small one, so that by loosening the screw 39 and drawing the member 37 back it causes the ear 45 of the vibrator to be moved nearer to the pin 62 upon which the work clamp oscillates, and causes a

longer throw of the work clamp, or by moving the member 37 forward the throw of the work clamp is decreased.

To line the device up with the needle of the sewing machine the screw 32 is loosened and the member 33 can be moved in either direction, thus carrying the pivot center of the vibrator to a position which will cause the knife to line up with the needle on the strokes which pass the needle through the

cut.

What I claim for my invention is:

1. The combination with a frame and a work clamp mounted to reciprocate thereon and to vibrate laterally, of a stud, a ratchet cam with five points and working faces mounted on the stud, means for advancing the ratchet cam step by step, the work clamp having a vibrating means connecting it to the ratchet cam, a knife shield carried by the work clamp and movable thereon, a spring member, a knife carried by the spring member adapted to be forced through the material by the needle bar, a yoke formed on the end of the spring member, a rotating cam on said stud, a cam face formed on said yoke and acting in conjunction with the rotating cam on the aforesaid stud, and a spring formed on said yoke for operating the knife at the proper time and withdrawing it from under the needle bar.

2. The combination with a frame and a work clamp mounted to reciprocate thereon and to vibrate laterally, of a stud, a ratchet cam with five points and working faces mounted on the stud, a pawl plate for advancing the ratchet cam step by step, the work clamp having a vibrating means connecting it to the ratchet cam, a knife shield carried by the work clamp and movable thereon, a spring member, a knife carried by the spring member adapted to be forced through the material by the needle bar, a yoke formed on the end of the spring member, a rotating cam on said stud, a cam face formed on said yoke and acting in conjunction with the rotating cam on the aforesaid stud, and a spring formed on said yoke for operating the knife at the proper time and withdrawing it from under the needle bar.

3. The combination with a frame and a work clamp mounted to reciprocate thereon and to vibrate laterally, of a stud, a ratchet cam with five points and working faces mounted on the stud, a pawl plate for advancing the ratchet cam step by step, the work clamp having a vibrating means connecting it to the ratchet cam, means for preventing any backward throw of the ratchet cam, a knife shield carried by the work clamp and movable thereon, a spring member, a knife carried by the spring member adapted to be forced through the material by the needle bar, a yoke formed on the end of the spring member, a rotating

cam on said stud, a cam face formed on said yoke and acting in conjunction with the rotating cam on the aforesaid stud, and a spring formed on said yoke for operating the knife at the proper time and withdrawing it from under the needle bar.

overstitch or the lateral throw of the work clamp, a knife shield carried by the work clamp and movable thereon, a spring member, a knife carried by the spring member adapted to be forced through the material by the needle bar, a yoke formed on the end of the spring member, a rotating cam on said stud, a cam face formed on said yoke and acting in conjunction with the rotating cam on the aforesaid stud, and a spring formed on said yoke for operating the knife at the proper time and withdrawing it from under the needle bar.

4. The combination with a frame and a work clamp mounted to reciprocate thereon and to vibrate laterally, of a stud, a ratchet cam with five points and working faces mounted on the stud, a pawl plate for advancing the ratchet cam step by step, the work clamp having a vibrating means connecting it to the ratchet cam, means for shifting at certain periods the pivot upon which the work clamp oscillates to form a button-hole with a loop to make an eyelet end, a knife shield carried by the work clamp and movable thereon, a spring member, a knife carried by the spring member adapted to be forced through the material by the needle bar, a yoke formed on the end of the spring member, a rotating cam on said stud, a cam face formed on said yoke and acting in conjunction with the rotating cam on the aforesaid stud, and a spring formed on said yoke for operating the knife at the proper time and withdrawing it from under the needle bar.

7. The combination with a frame and a work clamp mounted to reciprocate thereon and to vibrate laterally, of a stud, a ratchet cam with five points and working faces mounted on the stud, a pawl plate for advancing the ratchet cam step by step, the work clamp having a vibrating means connecting it to the ratchet cam, means for preventing any backward throw of the ratchet cam, means for shifting at certain periods the pivot upon which the work clamp oscillates to form a button-hole with a loop to make an eyelet end, means for increasing or decreasing the overstitch or the lateral throw of the work clamp, a knife shield carried by the work clamp and movable thereon, a spring member; a knife carried by the spring member adapted to be forced through the material by the needle bar, a yoke formed on the end of the spring member, a rotating cam on said stud, a cam face formed on said yoke and acting in conjunction with the rotating cam on the aforesaid stud, and a spring formed on said yoke for operating the knife at the proper time and withdrawing it from under the needle bar.

30 5. The combination with a frame and a work clamp mounted to reciprocate thereon and to vibrate laterally, of a stud, a ratchet cam with five points and working faces mounted on the stud, a pawl plate for advancing the ratchet cam step by step, the work clamp having a vibrating means connecting it to the ratchet cam, means for preventing any backward throw of the ratchet cam, means for shifting at certain periods 40 the pivot upon which the work clamp oscillates to form a button-hole with a loop to make an eyelet end, a knife shield carried by the work clamp and movable thereon, a spring member, a knife carried by the spring member adapted to be forced through the material by the needle bar, a yoke formed on the end of the spring member, a rotating cam on said stud, a cam face formed on said yoke and acting in conjunction with the rotating cam on the aforesaid stud, and a 45 spring formed on said yoke for operating the knife at the proper time and withdrawing it from under the needle bar.

8. The combination with a frame and a work clamp mounted to reciprocate thereon and to vibrate laterally, of a stud, a ratchet cam with five points and working faces mounted on the stud, a pawl plate for advancing the ratchet cam step by step, the work clamp having a vibrating means connecting it to the ratchet cam, means for shifting at certain periods the pivot upon which the work clamp oscillates to form a button-hole with a loop to make an eyelet end, means for increasing or decreasing the overstitch or the lateral throw of the work clamp, means for adjusting the vibrating means relatively to the stud and needle, a knife shield carried by the work clamp and movable thereon, a spring member, a knife carried by the spring member adapted to be forced through the material by the needle bar, a yoke formed on the end of the spring member, a rotating cam on said stud, a cam face formed on said yoke and acting in conjunction with the rotating cam on the aforesaid stud, and a spring formed on said yoke for operating the knife at the proper 110

55 6. The combination with a frame and a work clamp mounted to reciprocate thereon and to vibrate laterally, of a stud, a ratchet cam with five points and working faces mounted on the stud, a pawl plate for advancing the ratchet cam step by step, the work clamp having a vibrating means connecting it to the ratchet cam, means for shifting at certain periods the pivot upon which the work clamp oscillates to form a button-hole with a loop to make an eyelet end, means for increasing or decreasing the

time and withdrawing it from under the needle bar.

9. The combination with a frame and a work clamp mounted to reciprocate thereon and to vibrate laterally, of a stud, a ratchet cam with five points and working faces mounted on the stud, a pawl plate for advancing the ratchet cam step by step, the work clamp having a vibrating means connecting it to the ratchet cam, means for preventing any backward throw of the ratchet cam, means for shifting at certain periods the pivot upon which the work clamp oscillates to form a button-hole with a loop to make an eyelet end, means for increasing or decreasing the overstitch or the lateral throw of the work clamp, means for adjusting the vibrating means relatively to the stud and needle, a knife shield carried by the work clamp and movable thereon, a spring member, a knife carried by the spring member adapted to be forced through the material by the needle bar, a yoke formed on the end of the spring member, a rotating cam on said stud, a cam face formed on said yoke and acting in conjunction with the rotating cam on the aforesaid stud, and a spring formed on said yoke for operating the knife at the proper time and withdrawing it from under the needle bar.

10. The combination with a frame and a work clamp mounted to reciprocate and to vibrate, of a cam having a series of arc faces meeting at points and having a concentric circular series of perforations double in number to the said faces, and advancing means arranged to engage said perforations to engage the cam at said perforations to turn the cam step by step, the work clamp

having a vibrating means connecting it to the ratchet cam, a knife shield carried by the work clamp and movable thereon, a spring member, a knife carried by the spring member adapted to be forced through the material by the needle bar, a yoke formed on the end of the spring member, a stud, a rotating cam on said stud, a cam face formed on said yoke and acting in conjunction with the rotating cam on the aforesaid stud, and a spring formed on said yoke for operating the knife at the proper time and withdrawing it from under the needle bar.

11. The combination with a frame and a work clamp mounted to reciprocate and to vibrate, of a cam having a series of arc faces meeting at points and having a concentric circular series of shoulders double in number to the said faces, and advancing means arranged to engage said shoulders to turn the cam step by step, the work clamp having a vibrating means connecting it to the ratchet cam, a knife shield carried by the work clamp and movable thereon, a spring member, a knife carried by the spring member adapted to be forced through the material by the needle bar, a yoke formed on the end of the spring member, a stud, a rotating cam on said stud, a cam face formed on said yoke and acting in conjunction with the rotating cam on the aforesaid stud, and a spring formed on said yoke for operating the knife at the proper time and withdrawing it from under the needle bar.

Signed at New York in the county of New York and State of New York this 10th day of September A. D. 1923.

ALBERTUS B. MATTINGLY.
